UNITED STATES PATENT OFFICE.

HENRI BERNAY, OF SAN FRANCISCO, CALIFORNIA, ASSIGNOR, BY MESNE ASSIGNMENTS, TO FRED W. THURSTON, OF SAN FRANCISCO, CALIFORNIA.

DRILL.

1,355,793.

Specification of Letters Patent. Patented Oct. 12, 1920.

Application filed February 24, 1919, Serial No. 279,001. Renewed April 6, 1920. Serial No. 371,738.

To all whom it may concern:

Be it known that I, HENRI BERNAY, a citizen of the United States, residing in the city and county of San Francisco, State of California, have invented a new and useful Improvement in Drills, of which the following is a specification.

The present invention relates to improvements in rock drills and the like wherein a detachable bit operates in conjunction with a slotted stock to prevent splitting of the stock when a pressure is applied to the cutting edge of the bit.

The primary object of the present invention is to provide an improved rock drill having a detachable bit.

A further object of the invention is to provide a device of the character described having improved means for attaching a bit to a slotted stock in such a manner that a pressure applied to the cutting edge of the bit will tend to move the portions of the stock beyond the slot toward each other and thereby prevent splitting of the stock.

A further object of the invention is to provide improved means for securing a bit within a slotted stock, said means being adapted to facilitate the insertion and removal of the bit.

Other objects and advantages will hereinafter more fully appear.

I accomplish these several objects by means of the improved device disclosed in the drawings forming a part of the present specification wherein like characters of reference are used to designate similar parts throughout the said specification and drawings, and in which:

Figure 1 is an elevation of my improved drill;

Fig. 2 is a side elevation of Fig. 1;

Fig. 3 is a vertical sectional view taken on line 3-3 of Fig. 2 in the direction indicated;

Fig. 4 is a bottom view of Fig. 1;

Fig. 5 is a top plan view of a bit removed from the stock;

Fig. 6 is a front elevation of Fig. 5;

Fig. 7 is a bottom view of the stock with the bit removed; and

Figs. 8 and 9 are an elevation and bottom view of a modified form of bit.

Referring to the drawings the numeral 1 is used to designate a stock bored centrally

as at 2 and provided with a centrally disposed transverse slot 3 whose walls converge toward the end of said stock 1. The ends of the stock 1 beyond the open end of the slot 3 are beveled and diverge from said slot 3 toward the sides of the stock 1 as at 4. 55

The stock 1 is also provided with annular grooves 6 arranged between the ends of the slot 3, the purpose of which will herein-after be more fully set forth.

A bit 7, provided with at least one transverse cutting edge 8, has beveled surfaces 9 to engage the bevel surfaces 4 of the stock 1, said beveled surfaces 9 operating to tend to move the ends of the stock beyond the slot 3 toward each other when a pressure is applied to the cutting edge 8 of the bit 7 to prevent splitting of said stock 1. 65

The bit 7 is also provided with an extension 11 shaped to fit into the slot 3 and slightly shorter than said slot so that when a pressure is applied to the cutting edge 8 the inner end of the extension 11 will not be forced against the inner end of the said slot 3, to prevent splitting of the stock 1. 70

As the slot 3 is narrower at its outer end the shape of said slot will prevent a longitudinal movement of the extension 11 of the bit 7 within said stock 1. 75

The extension has formed on its sides recesses 12 which register with the annular grooves 6 in the stock 1. 80

Rings 14 are rotatably mounted within the grooves 6 and recesses 12 when the beveled surfaces 9 and 4 are in engaging relation. Each ring 14 is provided with a gap 90 16 smaller than the width of the slot 3, the ends of said rings 14 being beveled as at 17 to facilitate insertion and removal of the extension 11 within the slot 3 when removing or inserting a bit. 95

The bit 7 is bored transversely as at 18 and has a longitudinal bore 19 through the cutting edge 8 and intersecting the first mentioned bore 18. The surfaces of the extension 11 are provided with recesses or 100 grooves 21 which operate in conjunction with the central bore 2 of the stock 1 to provide a passage for water when drilling.

To remove the bit the gaps 16 in both rings 14 are moved to register with either end of the slot 3. As the gaps 16 in said rings 14 are slightly smaller than the width or thickness of the extension 11 it is evi-

dent that said rings 14 will still prevent a movement of said extension 11 within the slot 3.

But, by applying a slight pressure of the 5 end of the extension 11 against the beveled ends 17 of the rings 14 said rings will be slightly expanded to increase the width of the gap to an extent sufficient to permit the passage of the extension 11 through said 10 gaps.

In replacing a bit the end of the extension is similarly pressed against the beveled ends 17 of the rings 14 to expand said rings an extent sufficient to permit the entrance of 15 said extension 11.

The probability of both gaps inadvertently registering with the same end of the slot 3 simultaneously when said gaps have been spaced apart is exceedingly remote, 20 and should the condition occur it is evident that the gap 16 would be insufficient for the passage of the extension and the bit would be retained in position.

In operation, when a pressure is applied 25 to the cutting edge 8 of the bit such a pressure is transmitted to the beveled surfaces 9 of said bit which engage the beveled surfaces 4 beyond the open end of the slot 3 of the stock 1 and tend to move said ends toward instead of away from each other thereby tending to prevent splitting the stock 1.

In Figs. 8 and 9 of the drawings, I have disclosed a modified form of bit 7' provided with two cutting edges 8' in the well known 35 cruciform type which may be used advantageously with the drill.

Having thus described my invention, what I claim as new and desire to secure by Letters Patent is—

40 1. A drill comprising a stock having a transverse slot therein, the walls of said slot converging toward the end of the stock; a bit having a extension shaped to fit the slot and detachably engaging said slot and rings 45 rotatably mounted upon the stock and the extension and having gaps therein, said gaps being smaller than the thickness of the bit extension.

2. A drill comprising a stock having a 50 transverse slot therein; a bit having at least one cutting edge and an extension shaped to fit the slot, said bit being arranged to engage the ends of the stock on each side of the slot and tend to move said ends toward each other when a pressure is applied to the cutting edge of the bit to prevent splitting of the stock; and rings rotatably mounted upon the stock and bit extension, said rings 55 having a gap therein slightly smaller than the width of the extension.

3. A drill comprising a stock having a transverse slot therein; the ends of the said 60 stock beyond the slot being beveled; a bit having at least one cutting edge and an extension shaped to fit the slot and beveled

surfaces to engage the bevel ends of the stock and tend to move said ends toward each other when a pressure is applied to the cutting edge of the bit whereby splitting of the stock may be prevented; and rings rotatably mounted upon the stock and the extension of the bit to prevent a movement of the extension within the slot and thereby secure the bit to the stock, said rings each having a gap therein of smaller width than 7 the width of the extension.

4. A drill comprising a stock having a transverse slot therein; a bit having an extension mounted within the slot; and rings rotatably mounted around the stock and bit 8 extension to prevent a movement of said extension within the slot, said rings each having a gap therein smaller than the width of the extension and provided with beveled ends to facilitate the removal and insertion 8 of said extension within said slot.

5. A drill comprising a centrally bored stock having a transverse slot therein intersecting said central bore; a bit having a cutting edge and an extension arranged to engage the slot, said extension being bored laterally and provided with grooves on each face of the extension and communicating with said bore, and a second bore through the body and cutting edge of the bit communicating with the first mentioned bore; and means for preventing a movement of the extension within the slot.

6. A drill comprising a centrally bored stock having a transverse slot therein intersecting said central bore; a bit having a cutting edge and an extension arranged to engage the slot, said extension being bored laterally and provided with grooves on each face of the extension and communicating with the said bore, and a second bore through the body and cutting edge of the bit communicating with the first mentioned bore; and rings rotatably mounted upon the stock and the extension of the bit to secure the bit to the stock, said rings each having a gap therein smaller than the width of the slot.

7. A drill comprising a stock having a transverse slot therein, the walls of said slot converging toward the end of the stock and the ends of the stock being beveled in opposite directions on each side of the open end of the slot; a bit having at least one cutting edge and beveled surfaces to engage the beveled ends of the stock whereby a pressure applied to the cutting edge of the bit will cause said surfaces to tend to move said beveled ends toward each other and thereby prevent splitting of the stock, said bit being provided with an extension shaped to fit the slot but of a shorter length than said slot whereby no pressure will be applied by the end of the extension onto the inner end of the slot; and means for pre-

venting a movement of the extension within the slot.

8. A drill comprising a stock having a transverse slot therein, the walls of said slot converging toward the end of the stock and the ends of the stock being beveled in opposite directions on each side of the open end of the slot; a bit having at least one cutting edge and beveled surfaces to engage 10 the beveled ends of the stock whereby a pressure applied to the cutting edge of the bit will cause said surfaces to tend to move said beveled ends toward each other and thereby prevent splitting of the stock, said bit 15 being provided with an extension shaped to fit the slot but of a shorter length than said slot whereby no pressure will be applied by the end of the extension onto the end of the slot; and rings rotatably mounted upon 20 the stock and extension to prevent a movement of said extension within the slot, said rings having a gap therein smaller than the width of the slot and beveled ends adjacent said gap to facilitate removal and insertion 25 of the extension when said gaps register with the slot.

9. A bit having a transverse cutting edge and a reduced extension substantially rectangular in cross section and provided with 30 locking recesses in each end of said extension, said bit being bored transversely

through said extension and longitudinally through the cutting edge to the first mentioned bore.

10. A bit having at least one transverse cutting edge and a reduced extension narrower in width than the length of said cutting edge, said extension tapering toward the bit and bored transversely and likewise bored through the cutting edge to the first mentioned bore, and grooves on each face of the extension also communicating with said first mentioned bore, and having beveled surfaces converging from the sides of the bit to the base of the extension. 45 40 35

11. A bit having at least one transverse cutting edge and a reduced extension narrower in width than the length of said cutting edge, said extension tapering toward the bit and bored transversely and likewise bored through the cutting edge to the first mentioned bore, and grooves on each face of the extension also communicating with said first mentioned bore, and having beveled surfaces converging from the sides of the bit to the base of the extension, and locking recesses formed in the sides of the extension and at right angles to the cutting edge. 50 55

In witness whereof, I hereunto set my signature.

HENRI BERNAY.
